BUFFING OR POLISHING WHEEL

Elisha W. Hall, Scituate, Mass.

Application September 16, 1937, Serial No. 164,197

2 Claims. (CL. 51—193)

This invention relates to a novel and improved buffing or polishing wheel. In connection with the finishing of tin plate or black iron sheets, long buffing or polishing wheels or rolls are used, usually made up of two or more axially elongated wheels placed end to end. It is desirable that the buffing or polishing material be firmly compacted by axial pressure, but heretofore the fact that the hubs have been non-compressible has prevented the desired compacting even when cup-shaped clamping plates are employed and a pressure of twenty tons exerted.

In accordance with this invention, the hubs are readily compressible when supplied to the user, and thus it is possible to compact the buffing or polishing material to the desired extent even with flat clamping plates because the hubs present but little resistance and their length can be reduced enormously. Using a pressure of say twenty tons, the buffing material can easily be reduced to one half, or even less, its original length. For example, a roll ninety-six inches long can be squeezed down to about forty-four to fifty inches.

The invention will best be understood by reference to the following description when taken in connection with the accompanying drawings illustrating the method and the product thereof, while its scope will be pointed out more particularly in the appended claims.

In the drawings:

Fig. 1 is an elevation of the face of one of the compressible disks employed in making up the hub;

Fig. 2 is an edge elevation of the same;

Fig. 3 is an elevation of a strip of bias-cut cloth to be employed as the buffing or polishing material;

Fig. 4 is an elevation of the strip ruffled to reduce its length along one of its edges;

Fig. 5 is a development of the ruffled edge of the strip;

Fig. 6 is an elevation illustrating the mode of making up the hub;

Fig. 7 is an elevation, partly in vertical section, illustrating one mode of assembling the ruffled strip with the hub;

Fig. 8 is a vertical, sectional view illustrating the mode of compressing the sleeve of buffing or polishing material in an axial direction without compressing the hub; and

Fig. 9 is a vertical, sectional view of a completed buffing or polishing wheel in readiness to be shipped to the user.

Referring to the drawings and to the method

and product illustrated therein by way of example, and having reference at first to Fig. 1, there is shown a disk 11 of readily compressible nature, the one shown consisting of corrugated cardboard comprising two outer, flat sheets 13 and an intermediate, corrugated sheet 15, all of which are adhesively united. This material is readily compressible or collapsible because of its cellular characteristic. The disk is provided with a central hole 17 of the required shape and dimensions to fit the arbor on which it is to be used, the hole shown being square.

One convenient way of building up a hub of the required length (see Fig. 6) is to place disks one at a time upon a square arbor 19 which fits the holes 17, and to apply adhesive such as silicate to the upper face of each disk before placing another disk upon it. When the desired length has been attained, the hub is removed from the arbor and laid aside.

The buffing or polishing material may be appropriate cloth such as canton flannel, twill, duck, or sheeting, bias-cut to form a strip 21 (see Fig. 3). In this example, this strip is single ply, but plural ply may be employed if desired. The strip is prepared for use by shortening one of its edges as by ruffling the same (see Figs. 2 and 3) and securing the ruffles as by one or more, herein two rows 23 and 25 of stitches. This may conveniently be accomplished by the use of a two-needle sewing machine equipped with a ruffling attachment.

The next step may be varied somewhat, as desired. The strip may be helically wound and its convolutions adhesively secured together to form a sleeve which is then applied by adhesive to and about the hub, or the strip may be helically wound about the hub and the convolutions adhesively secured to one another and to the hub as the winding progresses. This latter way is preferred and is illustrated in Fig. 7.

This step is conveniently carried out by the use of a horizontally rotatable turntable 27 to which is affixed an upright, square arbor of the same dimensions as the opening in the hub, the turntable being rotated by appropriate mechanism which it is deemed unnecessary to describe. First, a canvas or other suitable anchor disk 29, provided with a square opening the same size as the arbor is placed down about the latter and upon the turntable. The upper surface of this disk is coated with adhesive, such as latex, either before or after being placed on the turntable as by the use of a spray nozzle 31.

The hub is then slipped downwardly about the

arbor onto the coated surface of the disk. The hub is then temporarily lengthened by the use of a hub extension, herein a tube 33 whose descent is limited as by turning the inside of the 5 tube to fit the hub snugly and to provide a shoulder 35 to rest upon the upper end of the hub. The ruffled strip, of indefinite length, has its free end laid upon the projecting margin of the disk and suitably secured in place as by a thin clamp. 10 The turntable is then rotated and the strip is helically coiled about the hub, while adhesive such as latex is applied as by the nozzle to the successive convolutions near the inner margin and to the periphery of the hub. This is con- 15 tinued until there is built up about the hub and about the hub extension a sleeve which is much longer than the hub itself. Then the strip is severed, preferably at a point in line with the first end. 20 The hub and its extension, with the sleeve thereon, is removed from the arbor and placed between upper and lower platens 37 and 39 of a powerful hydraulic press, and with a hollow pres- 25 sure member such as a tube 41 between the upper platen and the upper end of the cloth sleeve, so that it telescopes about the hub extension. The length of this tube should be such that it will compress the cloth sleeve to the desired extent without the upper platen striking the upper end 30 of the hub extension. As a further precaution, or to permit the use of a shorter tube, the upper platen may be provided with an opening 43 of sufficient size to receive the hub extension. To prevent the cloth sleeve from being compressed 35 more than the desired amount, stops in the nature of blocks 45 may be placed at the sides of

the cloth sleeve and the lower end of the tube 41 will strike them.

Power is then applied to the press, and its plunger 47 raises the lower platen. The compression and the consequent shortening of the cloth 5 sleeve should be continued until the sleeve is considerably shorter than the hub because the cloth, being resilient, will expand somewhat. In practice, the compression is continued to the point where after the pressure is removed, the length 10 of the sleeve will approximate that of the hub. The assembly is then removed from the press and a second anchor disk 49 applied with adhesive such as latex. The completed wheel is now ready for shipment to the user. As before stated, when 15 the wheel is assembled end to end with others on an arbor, and clamping pressure applied, the hub, being readily compressible, yields and presents no obstacle to compression of the cloth sleeve to the desired extent. 20

Having thus described the invention, what I claim and desire by Letters Patent to secure is:

1. A buffing or polishing wheel comprising, in combination, a hub which is readily compressible in an axial direction, and a fabric sleeve about 25 said hub, said sleeve being less readily compressible than said hub.

2. A buffing or polishing wheel comprising, in combination, a hub composed of a plurality of 30 disks which are cellular in nature and which render said hub readily compressible in an axial direction, and a fabric sleeve about said hub, said sleeve being less readily compressible than said hub.
